CLAIM

The ornamental design for a vehicle wheel, as shown and described.

DESCRIPTION

FIG. 1 is a front view of a vehicle wheel showing our new design;

FIG. 2 is a cross sectional view thereof, taken along line 2-2 in FIG. 1; and,

FIG. 3 is a perspective view thereof.

Any broken lines represent an internal boundary of the design; the line itself and the area within form no part of the claim.
